L. L. PRATT.

PUMP.

APPLICATION FILED NOV. 15, 1912.

1,139,071.

Patented May 11, 1915.

5 SHEETS—SHEET 1.

Inventor

Louis L. Pratt.

Witnesses

H. Strauss

R. D. Krenkel

Joshua R. Potts.

Attorney

1,139,071.

L. L. PRATT.

PUMP.

APPLICATION FILED NOV. 15, 1912.

Patented May 11, 1915.

5 SHEETS—SHEET 2.

Inventor

Louis L. Pratt,

Witnesses

Ch. Strauss
R. D. Krenkel

By Joshua R. Potts.

Attorney

1,139,071.

L. L. PRATT.

PUMP.

APPLICATION FILED NOV. 15, 1912.

Patented May 11, 1915.

5 SHEETS-SHEET 3.

Inventor

Louis L. Pratt

Witnesses

H. Strauss
R.M. Brenkel

By Joshua R. P. Otto

Attorney

1,139,071.

UNITED STATES PATENT OFFICE.

LOUIS L. PRATT, OF PHILADELPHIA, PENNSYLVANIA.

PUMP.

1,139,071.

Specification of Letters Patent. Patented May 11, 1915.

Application filed November 15, 1912. Serial No. 731,475.

To all whom it may concern:

Be it known that I, LOUIS L. PRATT, a citizen of the United States, residing at Philadelphia, in the county of Philadelphia and State of Pennsylvania, have invented certain new and useful Improvements in Pumps, of which the following is a specification.

My invention relates to improvements in pumps, and more particularly to an improved suction or vacuum pump, which may of course be used as a compressor, the object of the invention being to provide a pump of this character which utilizes in a rotary member, spiral passages, through which water is compelled to move in separate slugs or sections, separated by slugs or sections of air, to induce a suction of air and create a partial vacuum.

A further object is to provide a pump of the character set forth which utilizes a stream or column of water under pressure and divides the water into separate slugs or sections causing the same to move around and also longitudinally of the rotary member, said slugs or sections of water constituting pistons, drawing in behind them, sections of air, so that a positive suction is had, and which, of course, by a slight reversal of parts may be utilized as a pressure device.

A further object is to provide a pump of this character which reduces friction to a minimum, which utilizes stuffing boxes merely to prevent leakage, and which are not subjected either to suction or pressure, and further provide a pump of this character having a rotary suction inducing member movable without contact with any other part.

With these and other objects in view, the invention consists in certain novel features of construction and combinations and arrangements of parts as will be more fully hereinafter described and pointed out in the claims.

In the accompanying drawings: Figure 1 is a view in longitudinal section of one form of my improved pump showing the rotary member in elevation. Fig. 2 is a view in section on the line 2—2 of Fig. 1. Fig. 3 is a view in elevation of the rotary member. Fig. 4 is a view in longitudinal section illustrating a modification. Fig. 5 is a view in section on the line 5—5 of Fig. 4. Fig. 6 is a view in elevation of the inner face of one of the end sections of the rotary element

illustrated in Fig. 4. Fig. 7 is a view in section on the line 7—7 of Fig. 4, and Fig. 8 is a view partly in section and partly in elevation illustrating another modification. 60

Referring to Figs. 1, 2, and 3, 1 represents the casing of my improved pump having removable heads 2 at opposite ends of the casing, and said heads 2 provided with integral brackets 3. These brackets 3 are provided with bearing sleeves 4 in which the shaft 5 is mounted. The particular bearing illustrated permits the shaft to run in oil, and is supplied with lubricant by a suitable member 6. 70

The shaft 5 projects through stuffing boxes 7 in heads 2, and has fixed thereto inside of casing 1, my improved rotary member 8. It is to be understood that the stuffing boxes 7 do not support the shaft, but are packed 75 sufficiently to prevent leakage due to the liquid following the shaft, but as no pressure from within or without is upon these stuffing boxes, their packing can be relatively loose, so that a minimum of friction 80 is had upon the shaft.

The rotary element 8 turns inside of a circular chamber 9 formed integrally with an air inlet 10, and a water inlet 11, so that the air is admitted to the central portion of 85 the rotary member and the water inlet discharges tangentially against the center of the rotary element at an angle to the air inlet for a purpose which will hereinafter appear. 90

The rotary element 8 comprises a body cylindrical in form but having a plurality of spiral grooves or passages 12 which extend from the center to the ends of the rotary member. These spiral grooves 12 are 95 separated by partitions 13 and the partitions 13 come together at the center of the rotary member forming sharp wedge-like walls 14. In the particular construction shown, I have illustrated two of these sharp cutting walls 100 at opposite sides of the rotary member, hence dividing the rotary element into two separate grooves or passages 12 at each side of the center of the rotary element, and all of a general spiral shape beginning at the center 105 and discharging at the end of the rotary element.

To form the grooves into separate passages, cylindrical shell sections 15 are forced onto the rotary element, and these sections 110 extend from the ends of the element to a point removed from the center of the ele-

ment, so that the element has free communication at its center with both the air inlet port 10 and the water inlet 11. Furthermore, it will be seen that the shell 15 is spaced from the circular chamber 9 so that there is no frictional engagement between the walls of either.

To prevent liquid in casing 1 finding its way into the center of the rotary element, 10 I provide around the shell sections 9, spirally coiled strips 16 which operate when the element is rapidly revolving to keep back any liquid which would tend to enter the circular chamber 9, but it is to be understood that these strips 16 do not contact with the walls of chamber 9, but are close enough to keep out the water by reason of the action of their walls upon the water due to the rapidly revolving rotary element. 15 An outlet 17 for both liquid and air is provided in the upper portion of casing 1, and I would have it understood that while, of course, the pump may be coupled up in various ways to do various work, this outlet 20 17 may be so arranged as to permit the water and air in the casing 1 to be lost. In other words, the water may be carried away to a sewer and the air discharged into the atmosphere, and in this simple form, 25 the water inlet 11 may be connected with any source of supply which gives a pressure, approximating atmospheric pressure at least. In other words, the pump may be connected up in a great many different 30 ways, and a simple form is to connect the water with any ordinary city supply, and of course, regulate the pressure to suit conditions.

In operation, assuming the water to be 40 under pressure and entering through port 11; the rotary element 8 will be rapidly revolved in the direction of the arrow indicated in Fig. 2. As each wedge shaped sharp wall 14 comes into contact with the stream of water out of port 11, it will divide this stream of water and compel it to follow the grooves or passages 12. The wedge shaped sharp wall 14 then momentarily cuts off the supply of water, so that 45 the sections or slugs of water which have been taken into the grooves or passages 12, will induce a suction of air back of them, said air being drawn in through the inlet 10. The next wedge shaped wall 14 will 50 again cut off the water, so that the grooves or passages 12 will contain alternate slugs or sections of water and air, both moving rapidly toward the ends of the rotary element by reason of the spiral shape of the 55 grooves and the rapid rotation of the element.

The rotary element performs the function of dividing the stream of water into slugs or sections and compels said slugs 60 or sections to travel through the grooves

and draw between them sections of air, so that a plurality of liquid pistons are provided which are continuously moving in a circuitous path from the center to both ends of the rotary element, and thereby creating a positive suction to insure a partial vacuum.

By connecting the outlet 17 with some pressure chamber, it will be readily seen that the pump may be used for pressure purposes as well as for suction, but in any event, the operation will be the same. Furthermore, it will be noted that the rotary element turns in a direction to move its wedge shaped walls 14 against the incoming stream of water. In other words, the 80 water is discharged tangentially against the rotary element and against the end walls 14, but the rotary element is turning with sufficient rapidity to cut off this stream into slugs or sections of water and insure a suction of air between the slugs or sections.

In the modification illustrated in Figs. 4, 5, 6, and 7, the casing 18 in which the rotary element 19 is mounted to turn, is made in two halves or sections as illustrated in 90 Figs. 5 and 7 to facilitate the assemblage of the rotary element. This casing 18 is provided with heads 2, brackets 3, and bearings 4 to support the shaft 5 the same as in the form shown in Figs. 1, 2, and 3. The 95 shaft 5 also projects through stuffing boxes 7 in the heads 2, but receives its support from the bearings 4. This casing 18 has an air inlet 20 which communicates with a circular central chamber 21 in which the 100 intermediate portion 22 of the rotary element 19 is mounted to turn. A water inlet 23 also communicates with this central chamber 21, so that liquid and air are supplied to this chamber as in the form above 105 described. An outlet 24 is provided in the upper portion of the casing 18, and hence the water and air are free to escape. In this form of my invention, the rotary element 19 comprises three parts, namely, a 110 central member 22 and two end members 25. The central member 22 is formed with a plurality of wedge shaped partition walls 26, which operate like the walls 14 of the rotary element 8 to not only divide the 115 stream of water, but also cut off the stream of water momentarily. The end members 25 are formed with helical passages 27 which communicate at their inner ends with the opposite sides of the walls 26, and at 120 their outer ends discharge into the casing 18. Hence, when the shaft 5 is revolved, the rotary element acts precisely like the rotary element 8 to compel the water to flow in sections or slugs through the grooves 125 27 and induce a suction of air between the slugs or sections of water. To prevent the water from finding its way into the central chamber 21, the inner faces of the end sections 25 are provided with a circular series 130

of curved blades or vanes 28 which throw the water outwardly. It is to be understood that these blades or vanes do not touch metal, and hence the friction is reduced to 5 a minimum.

In the modification illustrated in Fig. 8, the casing 29 is provided with heads 2, brackets 3, bearings 4, shaft 5, and stuffing boxes 7 as in the forms above described. 10 This casing 29 is, however, divided by a vertical partition 30 into two chambers 31 and 32 through both of which shaft 5 projects. In chamber 31, a rotary water pump 33 is located and operated by the shaft 5, 15 said pump being connected by a pipe 34 with the water inlet 35 of my improved pump 36. The pump 36 illustrated in elevation in the chamber 32 corresponds in operation to the pumps above set forth, and I 20 would have it understood that either form of pump above described may be utilized in the chamber 31. In this modification the water does not escape through the outlet 37, but flows over the partition 30 and is utilized over and over again by the pump 33. 25 The operation of this device is like that above described, the air entering inlet 38 and through the medium of the slugs of water, drawn longitudinally of the rotary element, 30 and such air bubbling up through the water in the casing 32 and escaping through the outlet 37.

Various slight changes might be made in the general form and arrangement of parts 35 described without departing from my invention, and hence I do not limit myself to the precise details set forth, but consider myself at liberty to make such changes and alterations as fairly fall within the spirit and 40 scope of the appended claims.

Having thus described my invention, what I claim as new and desire to secure by Letters Patent is:

1. In an air pump, a chamber of circular 45 cross section provided in the periphery with a water inlet and an air inlet spaced apart circumferentially, a rotary impeller within said chamber and provided with a spiral passage way, and means for positively rotating said impeller, substantially as described.

2. In an air pump, a chamber provided 55 with an air inlet and a water inlet, the latter extending substantially tangentially into said chamber, a rotary impeller within said chamber and provided with a spiral passage way and means for positively rotating said impeller in a direction opposite to that of the inflowing water, substantially as described.

3. In a pump, the combination with a casing, of a rotary impeller mounted in the casing, a driving shaft secured to the rotary impeller and projecting through the casing, 60 said rotary impeller having a plurality of

circuitous passages beginning at the center of the rotary impeller and discharging into the casing, said casing having air and water inlets at an angle to each other, and both communicating with the center of the rotary 70 impeller, said rotary impeller having wedge shaped walls operating to separate the current of water into the several passages, and intermittently cut off the supply of water, whereby the water is divided in the passages 75 into a plurality of separate slugs or sections inducing a suction of air between them, substantially as described.

4. In a pump, the combination with a casing having a central circular chamber, and air and water inlet ports communicating with said circular chamber and located at an angle to each other, of a rotary impeller mounted to turn in the casing within the circular chamber and out of contact with the 80 walls of the latter, a driving shaft secured to the rotary impeller and projecting through the casing, said rotary impeller having a plurality of circuitous passages beginning at the center of the rotary impeller, and division walls on the rotary impeller constructed to intermittently cut off the supply of water, whereby the water in the passages is compelled to flow in a continuous series of separate slugs or sections and induce a suction of 85 air between them, said casing having an air and water outlet above said chamber whereby the latter remains submerged, and means on the rotary impeller for deflecting the water away from the central chamber in the 90 casing, substantially as described.

5. In a pump, the combination with a casing having a central circular chamber, and air and water inlet ports communicating with said chamber and located at an angle 105 to each other, of a cylindrical rotary impeller mounted to turn in said central chamber, a driving shaft secured to the rotary impeller and projecting through the casing, said rotary impeller having a plurality 110 of spiral grooves beginning at the center of the rotary impeller and extending to the ends thereof, and shell sections secured on the rotary impeller and extending over the grooves from their ends to points removed 115 from the center of the rotary impeller, substantially as described.

6. In a pump, the combination with a casing having a central circular chamber, and air and water inlet ports communicating 120 with said chamber, and located at an angle to each other, of a cylindrical rotary impeller mounted to turn in said central chamber, a driving shaft secured to the rotary impeller and projecting through the 125 casing, said rotary impeller having a plurality of spiral grooves beginning at the center of the rotary impeller and extending to the ends thereof, and shell sections secured on the rotary element and extending over 130

the grooves from their ends to points removed from the center of the rotary impeller, and means on the outside of the shell exerting pressure on the water in the casing 5 to move it toward the ends of the rotary impeller, substantially as described.

7. In a pump, the combination with a casing having a central circular chamber, and air and water inlet ports communicating 10 with said chamber, and located at an angle to each other, of a cylindrical rotary impeller mounted to turn in said central chamber, a driving shaft secured to the rotary impeller and projecting through the casing, 15 said rotary impeller having a plurality of spiral grooves beginning at the center of the rotary impeller and extending to the ends thereof, and shell sections secured on the rotary impeller and extending over the 20 grooves from their ends to points removed from the center of the rotary impeller, means on the outside of the shell exerting pressure on the water in the casing to move it toward the ends of the rotary impeller, 25 said means comprising spiral strips secured to the outer face of the shell sections, substantially as described.

8. In a pump, the combination with a casing, of a shaft mounted in said casing and 30 projecting beyond the ends thereof, a rotary impeller on said shaft in the casing, said casing having a circular chamber surrounding the central portion of the rotary impeller, and air and water inlets communicating 35 with said chamber at an angle to each other, and said rotary impeller having a plurality of circuitous passages beginning at the center of the rotary impeller and extending to the ends thereof, substantially as 40 described.

9. In a pump, a casing provided in its periphery with a water inlet and an air inlet spaced apart circumferentially, a rotary impeller in said casing and wedge shaped cut 45 off devices on the rotary impeller adapted to divide the water into a continuous flow of spaced slugs, said air and water inlets being arranged substantially in the path of 50 rotation of the apexes of said wedge shaped devices, substantially as described.

10. In a pump, the combination with a casing, of a rotary impeller in the casing, a driving shaft secured to the rotary impeller and projecting through the casing, 55 means for directing water and air into contact with the rotary impeller, said rotary impeller having a plurality of passages extend-

ing around the rotary impeller, and wedge shaped cut off devices on the rotary impeller directing the water into said passages and 60 intermittently cutting off the supply of water, whereby the water is compelled to move in sections or slugs through the passages, spaced apart, and induce a suction of air between them, substantially as described. 65

11. In a pump, the combination with a casing, of a rotary impeller mounted in the casing, a driving shaft secured to the rotary impeller and projecting through the casing, said rotary impeller having a plurality of circuitous passages beginning at the center of the rotary impeller and discharging into the casing, said casing having an air inlet communicating with the center of the rotary impeller and having a water 75 inlet adapted to direct water under pressure tangentially against the center of the rotary impeller, and both communicating with the center of the rotary impeller, said rotary impeller having wedge shaped walls 80 operating to separate the current of water into the several passages, and intermittently cut off the supply of water, whereby the water is divided in the passages into a plurality of separate slugs or sections inducing 85 a suction of air between them, substantially as described.

12. In a pump, the combination with a casing having a central circular chamber, of a rotary impeller mounted to turn in the 90 casing within the circular chamber and out of contact with the walls of the latter, said casing having an air inlet communicating with the center of the rotary impeller and having a water inlet adapted to direct water 95 under pressure tangentially against the center of the rotary impeller, said rotary impeller having a plurality of circuitous passages beginning at the center of the rotary impeller, and division walls on the rotary 100 impeller constructed to intermittently cut off the supply of water, whereby the water in the passages is compelled to flow in a continuous series of separate slugs or sections and induce a suction of air between 105 them, substantially as described.

In testimony whereof I have signed my name to this specification in the presence of two subscribing witnesses.

LOUIS L. PRATT.
